HIGH PRESSURE CASED CONTRACTION AND EXPANSION JOINT

Harry E. Hofwolt, Luverne, Minn.

Application August 23, 1937, Serial No. 160,512

3 Claims. (Cl. 94—18)

This invention relates to what is known as expansion joints, and its general object is to provide a joint of that character, which can be used with utmost efficiency in concrete work of all kinds, but is primarily designed for paving construction, such as concrete highways, roads, pavements, streets, alleys, etc., to compensate for expansion and contraction of paved sections, in any direction and to any extent, thereby eliminating any possibility of the sections cracking or becoming permanently out of alignment, as my joint not only acts as a filler, but actually and permanently secures or locks the sections together for relative movement.

An important object is to provide a joint of the character set forth, that includes companion casing members, initially held connected together in spaced relation, with highly compressed elastic filler material therein, that expands and contracts freely under all conditions, the casing members being disconnected from each other when the concrete sets, so as to allow independent movement thereof with respect to each other, as well as free expansion and contraction of the material, and the casing members are fixed to adjacent sections of concrete, for movement therewith, yet means are provided to hold the casing members associated and to prevent the concrete sections from being disposed out of alignment therewith and with each other.

A further object is to provide what may be termed a high pressure, steel cased, contraction and expansion paving joint that is water-tight, and trough means are provided and fixed to the casing members, to not only act to prevent moisture from passing to the soil below the concrete sections but also to fix the casing members to the sections.

Another object is to provide a joint of the character set forth, that also reinforces the concrete sections, is easy to lay, inexpensive to manufacture, simple in construction, and extremely efficient in use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a top plan view illustrating the

manner of using my joint in pairs for paving construction.

Figure 2 is a side elevation thereof.

Figure 3 is a transverse sectional view illustrating the joint in use.

Referring to the drawing in detail, it will be noted that the joints in the form as shown are used in aligned pairs disposed in end to end contact, and each joint includes a pair of companion casing members 1 which in the form as illustrated are tapered toward one end to follow the inclination of the road bed, and the lower edge of the members are inclined for that purpose. Each casing member is provided with a side wall 2 which is co-extensive with the length of the joint and the side walls have flanges 3 formed thereon and extending at right angles from the upper, lower and end edges thereof, for disposal toward each other. The flanges 3 are recessed as at 4 to provide tongues 5 between the recesses, and the casing members are constructed and arranged so that the tongues 5 of one member are aligned with the recesses of the opposed member, as clearly shown in Figure 1.

Disposed between or within the casing members is a mass 6 providing a filler and which may be of any material suitable for the purpose, but is preferably a composition of cork, rubber and asphalt, in that it has been found that such a composition has great expansion and contraction qualities under all weather conditions. In making the joint, the mass 6 is highly compressed between the casing members, and the side walls 2 thereof are provided with openings to receive headed pins 7 through which extends a key wire 8 for cooperation with the pins for holding the mass 6 in its compressed condition until such time that the joint is put into use and the concrete sets. In order to allow ready removal of the key wire 8, I provide sleeves 9 surrounding the wire, and when the wire is removed, it will be obvious that the casing members are then free to move inwardly in either direction toward and away from each other, yet the mass 6 is confined between the casing members due to the flanges 3.

Secured to the inner sides of the side walls 2 to be embedded within the mass 6, are flanged strips 10 which extend longitudinally of the walls and are co-extensive with the length thereof. The flanges of the strip 10 extend inwardly and upwardly, and the strips provide troughs, for cooperation with troughs 11 that are likewise formed from flanged strips bent at right angles upon themselves with the inner flanges fixed to the outer surfaces of the walls 2, with the outer

55

flanges disposed in parallelism therewith, as clearly shown in Figure 3. It will be obvious that the troughs prevent water, moisture and the like from seeping through the joint or between the 5 joint and the sections 12 of concrete, therefore moisture cannot reach the soil below the sections to cause damage by freezing and thawing.

The side walls are also provided with openings within which are slidably mounted reinforcing 10 rods 13 that are of a length to extend within a considerable distance of the concrete sections as shown in Figure 3, and the extending ends of the rods 13 have loosely mounted thereon sleeves 14 having closed outer ends. Surrounding the 15 rods 13 and disposed between the walls 2 for engagement therewith, are coil springs 15, which tend to urge the members apart and provide rigidity and strength to the joint.

From the above description and disclosure of 20 the drawing, it will be obvious that in using my joints in building concrete highways and the like, the joints are laid in companion pairs as suggested in Figures 1 and 2. The concrete is then poured in the usual manner to the height of the 25 joint as shown in Figure 3. When the concrete sets, the key wires 8 are removed from the pins 7, so that the pressure on the mass 6 is ultimately released, to allow expansion and contraction thereof, in accordance with the expansion and 30 contraction of the concrete sections which are held fixed to the casing members by the troughs 11, to prevent separation thereof, and the casing members together with the concrete sections are held in alignment against horizontal and vertical 35 displacement by the reinforcing rods 13.

It is thought from the foregoing description that the advantages and novel features of the invention will be readily apparent.

It is to be understood that changes may be 40 made in the construction and in the combination and arrangement of the several parts, provided that such changes fall within the scope of the appended claims.

What I claim is:

45 1. An expansion joint for concrete construction and comprising separable members cooperating to provide a casing including side walls, flanges formed on the upper, lower and end edges of the side walls and being recessed to provide 50 tongues, said members being arranged with respect to each other for disposing the tongues of one member in registration with the recesses of

the other member, a mass of elastic material within said casing, means for initially holding said casing members together with the material highly compressed and being releasable to allow independent movement of the casing members for free expansion and contraction of the mass of material, rods loosely mounted through the walls and extending upon opposite sides thereof, sleeves having closed outer ends and loosely surrounding the extending portions of the rods, and 10 moisture troughs secured to the inner and outer sides of the walls and extending longitudinally thereof.

2. An expansion joint for concrete construction 15 and comprising separable members cooperating to provide a casing including side walls, flanges formed on the side walls and being recessed to provide tongues, said members being arranged with respect to each other for disposing the tongues of one member in registration with 20 the recesses of the other member, a mass of elastic material within said casing, and means for initially holding said casing members together with the material highly compressed and being releasable to allow independent movement of the 25 casing members for free expansion and contraction of the mass of material.

3. An expansion joint for concrete construction and comprising separable members cooperating to provide a casing including side walls having 30 openings arranged therein in row formation, with the openings of one wall registering with those of the other, flanges formed on the side walls and being recessed to provide tongues, said members being arranged with respect to each other for 35 disposing the tongues of one member in registration with the recesses of the other member, a mass of elastic material within said casing, means for initially holding said casing members together with the material highly compressed and 40 being releasable to allow independent movement of the casing members for free expansion and contraction of the mass of material, said holding means including headed pins mounted in the registering openings, a key wire extending 45 through the pins and beyond one end of the members to facilitate removal of the wire from the pins, a sleeve surrounding the wire and disposed between the pins, and moisture troughs secured to said casing members.

HARRY E. HOFWOLT.
